Primary Examiner—Dominic Simone
Attorney, Agent, or Firm—Gary L. Eastman, Esq.

[57] CLAIM

The ornamental design for a bubbling display, as shown and described.

DESCRIPTION

FIG. 1 is a perspective view of a bubbling display showing our new design;

FIG. 2 is a front view thereof;

FIG. 3 is a right side view thereof;

FIG. 4 is a top plan view thereof; and,

FIG. 5 is a bottom plan view thereof.

The rear view of the bubbling display is a mirror image of FIG. 2, and the left side view of the bubbling display is a mirror image of FIG. 3.

1 Claim, 2 Drawing Sheets

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 402,585
DATED : December 15, 1998
INVENTOR(S) : Johnson et al.
